CLOSURE FOR KNOCK-OUT HOLES

Leroy M. Cox, Anaheim, Calif.

Application April 20, 1936, Serial No. 75,387

2 Claims. (Cl. 247—26)

This invention relates to devices used for closing holes in electric connection boxes that are customarily provided with so-called knock-outs and similar devices where a closing of holes can be accomplished in a similar manner.

One of the objects of this invention is to provide a cheap, reliable and durable closing device that may be quickly inserted or removed and still be substantially secure when in place.

10 Another object is to provide a device that may be quickly inserted or removed without the use of any tools where the application of tools might cause damage or at places that make the use of tools difficult.

15 Another object is to provide a device that can be applied from one side where the other side is inaccessible.

Another object is to provide a device that may be inserted or removed repeatedly without damage 20 to the device itself or to parts to which it is applied.

Another object is to provide a distinctly substantial device so designed and constructed that a loosening of parts becomes negligible if not impossible.

25 Another object is to provide a device that may be made of any required strength, thickness, or type of material, as against fire protection, and still embody the desired resiliency for ready insertion or removal.

Another object is to provide a device with retaining means suitable for a firm and constant engagement, tight and rattle-proof, while in place.

30 Other objects will appear from the following description and appended claims as well as from the accompanying drawing, in which—

Fig. 1 is a general mid-sectional view of one simple form of the device according to this invention.

40 Fig. 2 is a general mid-sectional view of a so-called knock-out.

Fig. 3 is a plan view as seen in the direction of the arrow 3 in Fig. 1.

45 Fig. 4 is a plan view of a so-called knock-out.

Fig. 5 is an edge view of a device of the form illustrated in Fig. 1, as it appears when partly removed or inserted.

50 Fig. 6 is an edge view of a slightly modified device as it appears when partly removed or inserted.

Fig. 7 is a plan view of the modified device as seen in the direction of the arrow 7 in Fig. 6.

55 Fig. 8 is a plan view of a knock-out of a slightly modified form.

Fig. 9 is a plan view of a knock-out of another slightly modified form of knock-out.

Electric connection or fuse boxes are customarily provided with so-called knock-outs of a type similar to the illustrations in Figs. 2 and 4, an electrician merely knocking out any number of such knock-outs required for the insertion of wires or other appliances.

Frequently, moreover, it becomes necessary to close a hole from which such a knock-out has been removed.

Such a closing, of course, must be done with due regard for safety and appearance.

Though I am aware that various devices for this purpose can be had on the open market, generally, however, I experienced unsatisfactory conditions, such as rattling, difficult to be inserted, difficult to remove, not tight, difficulty when only to be reached from one side, and many other disagreeable features, perhaps, not necessarily recited here.

The simple device illustrated in Figs. 1 and 3 is merely provided with a spring-like member 10, which may be secured in any suitable known or required manner, though a rivet has been indicated at 11, but it will readily be understood that spot-welding, soldering, or other means might be just as expedient, depending really largely on the material of the closure 12 itself, which, in turn, might be of various materials, depending largely on the use or requirements in different instances.

When the closure is made of sheet material it is preferably stamped as shown to form a shoulder edge 13, indicated in Fig. 3, to become snugly seated in a hole, or, particularly, against the edge 14, indicated in Fig. 1 of the material 15, in which a hole is to be closed.

If the closure is made of insulating material, such as bakelite, of course, it is not necessary to recess its outside as in a stamping, such as shown in Figs. 1, 3, 5, 6, or 7, and from this it should be understood that if made of other material it does not have to have a stamped appearance, though the shouldered edge 13 is of a preferred form, for the purpose desired here, as set forth above.

For inserting or removing this simple device of Figs. 1 and 3, one spring-end is simply shifted over the material 15 as indicated at 10a, until the opposite spring-end becomes free as indicated at 10b, when this device may easily be either removed or fully inserted.

To fully insert this device it is merely shifted in the opposite direction so that the spring-end 10b, will engage in a similar manner as spring- 55

end 10a until the shoulder 13 becomes seated against the edge 14 of the material 15 in the manner illustrated in Fig. 1.

When a removal is desired the device is simply tilted outwardly until the spring-end 10b points above or in front of the material 15 when the whole device may readily be withdrawn from the material 15, since the spring-end 10a is merely slightly frictionally engaging over the inside 10 of the material 15 in the illustration of Fig. 5.

The slightly modified form illustrated in Figs. 6 and 7 differs only in having about half of the spring member 10 of the device of Figs. 1, 3, and 5, the spring member 10c serving otherwise in a similar manner for removal and insertions, the engagement at the opposite side being completed by the lug 16, suitably depressed from the closure 12a, there being otherwise the same shoulder 13 to engage with the edge 14.

The illustrations of Figs. 8 and 9 merely show different shapes of knock-outs to make it clear that the shape of closures must be according to any requirement, and, as already stated, a closure may be made to suit requirements for other than in electric connection and fuse boxes and for any such other requirements the closure and its parts must, of course, be designed to make this invention applicable.

Having thus described my invention, I claim:—

1. In a device of the class described, in combination with a wall having an opening, a closing member comprising a first portion of larger dimensions than the opening engaging one surface of the wall adjacent the opening, a raised second portion of substantially lesser dimensions than the opening, integral with the first portion and for insertion within the opening, resilient radial means attached to the second portion and 10 engaging the other surface of the wall adjacent the opening.

2. In a device of the class described, in combination with a wall having an opening with an edge surrounded by inner and outer surfaces of the wall, a closing member comprising a first portion of larger dimensions than the opening to engage one surface, a raised second portion integral with the first portion and of substantially lesser dimensions than the opening, and 15 resilient means attached to the second portion at a point away from the edge inwardly and with its free termination extending beyond the contours of the opening outwardly to engage with the other surface.

LEROY M. COX.
